UNITED STATES PATENT OFFICE.

CHARLES C. FULGHUM, OF RICHMOND, INDIANA.

BOILER GRATE.

Application filed February 21, 1921. Serial No. 446,883.

To all whom it may concern:

Be it known that I, CHARLES C. FULGHUM, a citizen of the United States, residing in the city of Richmond, in the county of Wayne, State of Indiana, have invented new and useful Improvements in Boiler Grates, of which the following is a full, clear, and comprehensive specification and exposition, the same being such as will enable others familiar with the art to manufacture and install the same.

The object of this particular invention, broadly speaking, is to provide certain new and useful improvements in grates for the boilers of heating plants, the same being simple in character, strong and durable in construction, easily operated and controlled, positive and effective in action, and a device which can be provided at a comparatively low price.

More specifically stated, my object is to provide improvements in grates whereby the grate-bars can be rotated only by the crank provided therefor, and having means whereby when the crank is removed from operative position the grate bar will be locked in its proper normal position, and at the same time the aperture in the front of the boiler for the insertion of the crank stem will at all times be closed when the crank is removed.

Other minor and subsidiary objects of the invention will suggest themselves in the course of the following description, and that which is new will be correlated in the appended claims.

As further explanation it may be well to state that this application is a companion to two others filed herewith, entitled respectively: "Boiler for heating plants" and "Boiler magazine front."

The preferred means for carrying out my invention in a practical manner is shown in the accompanying drawings, in which—Figure 1 is an outside elevation of a portion of a boiler front, taken in the locality of the outer ends of two grate bars showing one of the cover plates in closed position and another in open position. Figure 2 is a side elevation, partly in section, taken in the line 2—2 of Fig. 1, Figure 3 is a side elevation, partly in section, taken on the line 3—3 of Fig. 1. Figure 4 is a perspective view of the forward end portion of one of the grate bars alone. Figure 5 is an inside face view of a portion of the boiler front. And Figure 6 is an end view of the stem of the operating crank.

Similar indices denote like parts throughout the several views. In order that the invention may be more fully understood and appreciated I will now take up a description thereof in detail.

It should first be understood that a series of grate bars A are arranged parallel and near to each other in the usual manner, and they are located immediately back of the boiler front or casing B, with their rear ends rotatably supported in the usual manner, while their front ends are each rotatably supported in a segmental or crescent bearing C which latter extends back from the rear face of the front B as shown in Fig. 5. A round aperture D is formed through the front B directly in alignment with and coaxial with the forward end of the grate-bar A and at the center of its upper edge a notch E extends upward forming a continuation of the opening D, as shown in Figs. 1 and 5.

Letter F denotes a crank which has a slightly flattened stem portion G, and integral with and extending at right-angles from one side of the stem G is the lug H.

Formed in the forward end of the grate-bar A, coaxial therewith, is the cavity I which corresponds in shape with, and which is adapted to receive therein the stem G of the crank. Extending out from one side of the cavity I is the smaller cavity J which is adapted to receive snugly therein the lug H, as shown in Fig. 3.

Located a short distance above the aperture D, in alignment with the notch E, is the hanger K which is secured to the face of the casing B by means of the bolts L.

Letter M denotes a cover-plate which is adapted to contact flat with the face of the front B and close the aperture D and the notch E, as in Fig. 2. Said plate has two pivots at its upper portion which are rotatably mounted by the prongs of the hanger K, as shown, whereby the plate M will always close by gravity when it is released, being adapted to be turned, as in Fig. 3, to expose the aperture D.

A lug N is formed integral with the rear face of the plate M, the same being of such size as to enter through the notch E and fill the cavity J, or nearly so, as shown in Fig. 2.

Operation: From the above it will now be seen that if the plate M be turned up, as at the right in Fig. 1, that the stem G of the crank F may then be inserted in the

cavity I, with the lug H at the same time entering the cavity J. Now by turning the crank F the grate-bar A will be rotated. After the above operation is complete then 5 the crank F may be removed, but only by bringing the lug H to position directly upward whereby it will register with the notch E, thereby insuring that the crank be removed only when the grate-bar is in its 10 normal operative position. Also as soon as the crank is removed the plate M will immediately turn downward by gravity thereby causing the lug N to enter the cavity J and thereby absolutely locking the grate-bar against rotation and also closing the 15 apertures D and E, thereby accomplishing in a simple and effective manner the objects of this invention.

I desire that it be understood that various 20 changes may be made in the several details of construction herein set forth without departing from the spirit of my invention and without sacrificing any of the advantages thereof which are new and useful.

25 Having now fully shown and described my invention, what I claim and desire to secure by Letters Patent of the United States, is—

1. Improvements in boiler grates, comprising in combination with a boiler casing 30 having an aperture therethrough a rotatable grate bar having a non-circular aperture formed in its end and registering with said aperture in the casing; a crank having 35 a stem portion adapted to be inserted through said aperture in the casing and en-

ter the aperture in the end of said grate bar, a cover plate hinged to said casing and above said aperture and adapted to close by gravity to cover said aperture in the 40 casing when said stem is removed, a lug carried by said cover plate and adapted to enter said aperture in said grate bar to lock the grate bar against rotation when said crank is removed.

2. Improvements in grates, comprising a rotatable grate bar having a cavity in its end with a smaller cavity extending out from the first mentioned cavity, a boiler casing covering said end of the grate bar 50 and having an aperture therethrough in alignment with said cavities in the grate bar, a crank, a stem integral with said crank and adapted to project through said aperture in the casing and enter the first mentioned cavity in the grate bar, a lug integral with said stem and adapted to enter said smaller cavity in the grate bar, a hanger secured to the face of the casing and above said aperture therein, a plate hinged to 60 said hanger and adapted to cover said aperture in the casing, and a lug carried by said plate and adapted to enter the said smaller cavity in the grate bar whereby the grate bar may be locked against rotation. 65

In testimony whereof I have hereunto subscribed my name to this specification in the presence of two subscribing witnesses.

CHARLES C. FULGHUM.
